DESIGN FOR A TABLECLOTH

Bert Elfenbein, Scarsdale, N. Y., assignor to Felix
Tausend & Sons, New York, N. Y.

Application July 18, 1939, Serial No. 86,063

Term of patent 3½ years

To all whom it may concern:

Be it known that I, Bert Elfenbein, a citizen of the United States, residing at Scarsdale, county of Westchester and State of New York, have invented a new, original, and ornamental Design for a Tablecloth, of which the following is a specification, reference being had to the accompanying drawing, forming part thereof, wherein the figure is a face view of a quarter section of the tablecloth showing my new design, the other three sections being identical with that here disclosed, arranged in proper relation to complete the tablecloth.

The characteristic features of my design reside in the scroll arrangements with inserts therein in combination with the more solid intermediate portion in twill weave, the design being executed in a contrasting thread to give a shadowy and contrasting effect.

I claim:

The ornamental design for a tablecloth, substantially as shown and described.

BERT ELFENBEIN.
